TOY WASHING MACHINE

Filed June 16, 1931

John Riemenschneider,
INVENTOR

Levi St. James
WITNESS:

BY *Victor J. Evans*
and *Co.* ATTORNEY

UNITED STATES PATENT OFFICE

JOHN RIEMENSCHNEIDER, OF MCKEESPORT, PENNSYLVANIA

TOY WASHING MACHINE

Application filed June 16, 1931. Serial No. 544,913.

My present invention has reference to a useful but amusing toy for children, and my object is the provision of a toy in the nature of a miniature motor operated clothes washer, in which the vacuum pounders are given the same vertical reciprocatory movement as that imparted to the pounders of regular or full sized washing machines, but in which the pounders are operated by a spring cam on the drive shaft of a clockwork, the said cam being in the nature of an elliptically wound spring, the shaft for the pounders resting upon said spring will, by its weight, partly compress the spring while the outer end of the spring will impart a kicking action against the shaft as the shaft rides off of the said spring.

To the attainment of the foregoing the invention consists in the improvement hereinafter described and definitely claimed.

In the drawings:

Figure 1 is an approximately central vertical longitudinal sectional view through the improvement.

Figure 2 is a top plan view.

Figure 3 is a detail side elevation of the cam spring.

The device is preferably constructed of stamped cheap metal in order to reduce the selling price thereof. However, any desired material may be employed in the construction of the improvement.

The device includes a hollow base 1 that affords a housing for a clockwork 2. The clockwork is of the usual construction and, therefore, has not been illustrated nor is it deemed necessary to describe the parts constituting the same. This spring is wound by a handle 3 that projects through the housing 1, and the driven shaft 4 of the clockwork has fixed on its outer end a spirally wound or cam spring 5.

To one side or edge at the top of the housing 1 there is hinged, as at 6, a shelf 7 and to the outer end of the shelf there is pivotally secured the straight end 8 of a support 9. The second or free end of the support is notched, as at 10, and the said notched portion is designed to engage with the outer wall of the housing 1 when the

shelf is in horizontal position. The support 9 has its notched end received through a vertically arranged elongated opening 11 of the housing so that the shelf, when the notched end of the support is moved out of contact with the wall of the housing may be swung against the side or end of the said housing and thus offer no projection when the shelf is not required for use. When in use the shelf is designed to contain thereon a clothes basket or tub 12.

Secured upon the flat top of the housing 1 there is the tub 13 of the improvement. The tub is normally closed by a hinged and flanged cover 14 and is provided with a handle or knob 15 to permit of the opening or closing of the said cover.

In and extending through the bottom of the tub and the top of the housing 1 there is a vertically arranged tube 16. The tube 16 terminates a suitable distance away from the top of the tub 13 and has received therein and provides a guide for a shaft 17 whose lower end rests on the cam spring 5. The top of the shaft has fixed thereon a spider 75 provided with depending legs 18 on each of whose lower ends there is fixed a vacuum pounder 19.

When the spring is wound the shaft 5 will be turned in the direction of the arrows disclosed by Figure 1 of the drawings. The spring cam will impart a vertical movement to the pounder or dasher 17. The weight of the shaft will partly compress the cam spring so that when the outer end thereof leaves the shaft 17 the cam spring will expand to a degree that will impart an upward kicking motion to the shaft 17. The shaft 17 returns downwardly and against the cam by its own weight and the weight added thereto by the spider and the vacuum pounders.

The tub 13 if desired may have at its outer end a water outlet pipe 20 that is normally closed by a plug 21 but the device being small in size will permit of the child draining water from the tub by merely tilting the bottom of the tub.

The toy is of an extremely simple nature and will attract the interest and afford amusement to the child possessing the same and it

is thought the foregoing will fully and clearly set forth the construction and advantages thereof to those skilled in the art to which the invention relates so that further detailed description will not be required.

5 Having described the invention, I claim:

In a toy washing machine, a tub having a tube therein, a shaft in the tube having a spider on the outer end thereof to which are 10 fixed vacuum pounders or the like, a clock-work, a shaft driven by the clockwork and a spirally wound spring on the shaft on which the lower end of the pounder shaft rests and which, by its weight, partly compresses the 15 spring and the said spring designed to exert, upon expansion, a picking action against the rod as the said rod rides off of the outer end of said spring.

In testimony whereof I affix my signature.

20 JOHN RIEMENSCHNEIDER.
